UNITED STATES PATENT OFFICE.

THOMAS A. HIBBINS, OF WELLSVILLE, OHIO, ASSIGNEE TO THE STEVENSON COMPANY, OF WELLSVILLE, OHIO.

DIE FOR HYDRAULIC OR STEAM PIPE PRESSES.

Application filed July 24, 1926. Serial No. 124,741.

My invention relates to improvements in dies for hydraulic or steam pipe presses.

The object of my invention is to provide a die for pipe presses of this character in which the clay is forced by a mud head through a cylinder and divided by corrugated arms arranged in the arch which divides the clay and after leaving the arms it is further compressed into a solid mass and discharged from the die proper, in a continuous form of pipe.

Another object of my invention is to provide a die for presses of this character in which means is provided for first forming the socket on the end of the pipe and then making the remainder of the pipe in a continuous operation, and severing the pipe from the remainder of the clay as it passes from the die, and at the same time providing means, whereby the die head which forms the socket at the lower end of the pipe also serves as means for supporting the pipe as it is formed in its passage from the die.

A further object of my invention is to provide a die for presses of this character in which the arch, the compressing chamber below the same, and the die proper, are made separately so that the same can be readily removed for repairs or replacement of new parts.

A still further object of my invention is to provide a compressor of this character in which the compressing chamber, the arch and the compressing chamber, therebelow, are all provided with linings of hard cast iron to prevent wear directly on the same.

A still further object of my invention is to provide a more effective die for presses of this character having certain details of structure and combination of parts herein after more fully set forth.

In the accompanying drawings:

Figure 1 is a vertical sectional view of the lower end of the mud cylinder, and showing the arch, the compressing chamber, and die, in section, and showing the die head in side elevation partly broken away.

Figure 2 is a horizontal sectional view taken on the line 2-2 of Figure 1, at the junction of connection between the arch and the lower compressing chamber.

Figure 3 is a horizontal sectional view taken on the line 3-3 of Figure 1.

Referring now to the drawings, 1 repre-

sents the mud cylinder, which as is well understood in the art, is filled with clay, or the like, and the clay is forced downwardly therethrough by a clay plunger which greatly compresses the clay. This cylinder 1 is provided with a lining 2, and is secured to the arch ring 3, as fully shown and described in my application filed July 24, 1926, Serial No. 124,740, and therefore needs no further description, as this forms no part of this invention. The arch ring 3 is provided with the arch 3' having three or more corrugated arms 4, which are equal distances apart and support at their inner ends the cylindrical member 5, which is screw threaded at its upper end as indicated at 6, and into which is screwed the plug 7 for closing the upper end thereof, to prevent the passage of clay into the same. The arch 3' is of hard steel and supports at its upper end the ring 9, having an inclined wall 10, as clearly shown in Figure 1 of the drawings. The lower end of the arch ring 3 is provided with an outwardly extending flange 11 to which is bolted the flange 12, by means of bolts 13, and said flange 12 is carried by the upper end of the choke ring 14. This choke ring 14 is provided on its inner face with an annular flange 15, adapted to support the choke liner 16, arranged entirely around the inner wall thereof. The upper end of the choke liner 16 is beveled inwardly as indicated at 17, terminating in the vertical wall 18. Extending downwardly from the vertical wall 18 is an outwardly extending oblique wall 19, terminating flush with the lower end of the choke chamber 14. The lower end of the choke ring 14 is provided with an annular flange 20 to which is bolted the flange 21 carried by the section 22 of the die proper. This die section 22 extends in an oblique inward direction, forming the slanting wall 23. The lower end of the die section 22 is provided with the vertical inner wall 24, connected to the outwardly extending oblique wall 25, which terminates in the vertical wall 26, having its lower end beveled as indicated at 27. The arch ring 3 is provided with a horizontally arranged opening 28 through which extends the shaft 29, which extends inwardly through one of the arms 4 into the cylindrical member 5, carried by the inner ends of the arms. The cylindrical member 5 is internally threaded as indicated at 30, and into which

is screwed the member 31, which is provided at its upper end with a vertical wall 32 terminating in the inwardly extending wall 33, and extending downwardly from the inwardly extending wall 33 is a vertical wall 34. The member 31, at the end of the vertical wall 34, is reduced as indicated at 35 and externally threaded, and upon which is screwed the inner ring member 36 of the die. This die ring member is provided with the obliquely arranged wall 37 terminating in the vertical wall 38, arranged opposite the vertical wall 24 of the die member 22. Thus, it will be seen that the passage 24' formed between the die members 22, and the ring member 36 of the die, is equal to the thickness of the pipe to be formed by the die. The shaft 29 within the cylindrical member 5 is provided with a beveled gear 39, meshing with the beveled gear 40 carried by the upper end of the shaft 41 arranged in the hollow cylindrical member 31. The lower end of the shaft 41 carries the knife for cutting the pipe as described in a separate application Serial No. 124,742, filed July 24, 1926, in which applicant has made claims for the specific construction of the knife and its operating mechanism. The die hoist piston 42 carries the die head 43, which has a reduced portion 44, which extends upwardly within the lower end of the die section 22, and spaced therefrom to form a socket on the lower end of the pipe of the shape shown in Figure 1 of the drawings. The beveled walls 25 of the die section 22 are provided with a series of valves 45 normally held closed by the springs, to hold them on their seats and prevent the clay from passing outwardly from the die. These valves will open by any suction, and thus allow air to pass into the die at the oblique wall 25, and break any vacuum or suction to allow the downward movement of the socket after it has been formed between the die head and the outer member 22 of the die. While I have shown this specific construction of valve it will be understood that any valve could be used, which would be closed by any outward pressure and would be opened by any inward pressure.

In the operation of my improved die, the clay is placed in the clay cylinder 1, and forced downwardly by the clay plunger, which forces the clay into the arch ring, and the corrugated arms 4 divide the clay, causing it to be divided. The clay then continues downwardly until it engages the beveled wall 17 of the choke liner, and continues downwardly into the enlarged space between the slanting wall 19 of the choke liner, and the walls 33 and 34, of the member 31. This allows the clay to be firmly united at the division lines, and it is continued to be forced downwardly and passes into the space between the slanting wall 23 and 37 of

the die member 22 and 36. These slanting walls greatly compress the clay and it passes outwardly through the vertical passage 24' between the vertical walls 24 and 38. It is understood that the die head 42 is in the position shown in Figure 1 of the drawings. The clay then fills the space between the die head and the walls of the two die members 22 and 36, forming the socket at the lower end of the pipe. After this socket has been formed the die head is gradually lowered and the clay plunger is continued to be forced downwardly, feeding clay through the several passages, as heretofore described. If, in the first downward movement of the clay plunger, there should be any suction at the slanting wall 25 of the outer die members on the socket the valves will open or break the suction or vacuum to allow the socket formed on the pipe to free itself and move downwardly. After this takes place it will be seen that a vertical pipe will be formed of a thickness equal to the space 24' between the vertical walls 24 and 38 of the die member. The die head supports the pipe until a pipe of desired length is formed, when the clay plunger and die head are stopped and the knife set into operation to sever the pipe from the body of clay passing from the die.

Having thus fully described my invention what I claim is:—

1. A pipe press comprising a clay cylinder, an arch below the cylinder for supporting the die part, means below the arch for compressing the clay, and a die below said compressing means for forming a pipe.

2. A pipe press comprising a clay cylinder, an arch below the cylinder for supporting the die part, a chamber below the arch for compressing the clay and allowing it to again expand, and a die in communication with the lower end of the chamber.

3. A pipe press comprising a clay cylinder, an arch for supporting the die part and forming the upper portion of the clay cylinder, a die below the arch, and a die head working in combination with the die for forming a socket on the lower end of the pipe.

4. A pipe press comprising a clay cylinder, an arch communicating with the cylinder for supporting the die part and forming the upper portion of the clay cylinder, an outer die member supported by the arch, and a central die member supported by the center of said arch.

5. A pipe press comprising a clay cylinder, an arch carried by the lower end of the cylinder, and having a central cylindrical hollow portion, a choke ring below the arch, an outer die member carried by the choke ring, and an inner die member carried by the central cylindrical member of the arch.

6. A pipe press comprising a clay cylin-

- der; an arch carried by the lower end of the cylinder and having a hollow central cylindrical portion; a choke ring carried by the lower end of the arch, an outer die member carried by the lower end of the choke ring, and a vertical member supported by the central cylindrical portion of the arch, and an inner die member carried by the lower end of the vertical member.
7. A pipe press comprising a clay cylinder, an arch carried by the lower end of the cylinder, a central cylindrical member carried by the arch, a choke ring carried by the lower end of the arch, an outer die member carried by the lower end of the choke ring, a vertical member secured within the lower end of the central cylindrical member carried by the arch, and extending downwardly through the choke ring, and an inner die member removably supported by the lower end of the vertical member.
8. A pipe press comprising a clay cylinder, an arch carried by the lower end of the cylinder and having a central hollow cylindrical portion, a choke ring carried by the lower end of the arch, an outer die member carried by the lower end of the choke ring, a vertical member removably secured within the lower end of the central cylindrical portion of the arch, and extending downwardly through the choke ring, an inner die member secured to the lower end of the vertical member, a vertical knife shaft passing through the vertical member and carrying a gear at its upper end within the central hollow cylindrical portion of the arch, a second gear meshing with the first gear, and a horizontal shaft carried by the second gear, and passing outwardly through the arch.
9. A pipe press comprising a clay cylinder, an arch supported by the cylinder, a choke ring carried by the lower end of the arch, an outer die member carried by the lower end of the choke ring, a vertical member supported by the central portion of the arch, a second die member secured to the lower end of the vertical member, and a die head cooperating with the die member to form a socket at the lower end of the pipe and to support the pipe as it is formed by the die.
10. A pipe press comprising a clay cylinder, an arch supported thereby, below the same, and having a central cylindrical portion, a choke ring carried by the lower end of the arch, an outer die member carried by the lower end of the choke ring and having an obliquely arranged wall converging into a vertical wall, and an outwardly and downwardly extending wall, relief valves arranged in said outwardly extending wall, a vertical member supported in the lower end of the central cylindrical portion of the arch, and extending through the choke ring, and a second die member car-

- ried by the lower end of the vertical member, and having a diverging wall terminating in a vertical wall of a greater length than the vertical wall of the outer die member.
11. A pipe press comprising a clay cylinder, an arch supported by the lower end of the cylinder, and having inwardly extending webs supporting at their inner ends a cylindrical member, a choke ring carried by the lower end of the arch, an outer die member carried by the lower end of the choke ring, a vertical member supported within the cylindrical member carried by the webs, and extending downwardly through the choke ring, and a second die member carried by the lower end of the said vertical member.
12. A pipe press comprising a clay cylinder, an arch carried by the lower end of the cylinder, a choke ring carried by the lower end of the arch, and having its inner wall extending obliquely inwardly, and then outwardly, a die member supported by the lower end of the choke ring, and a second die member supported by the arch.
13. A pipe press comprising a clay cylinder, an arch carried by the lower end of the cylinder, a choke ring carried by the lower end of the arch, and having its inner wall extending obliquely inwardly and terminating in a vertical wall, and extending from the lower end of the vertical wall in an oblique outward direction, an outer die member carried by the choke ring, and an inner die member supported by the arch.
14. A pipe press comprising a cylinder, an arch supported by the lower end of the cylinder, and having inwardly extending webs supporting the vertical hollow cylindrical member, a choke ring carried by the lower end of the arch, and having its inner wall converging inwardly and diverging outwardly, a die member carried by the lower end of the choke member, a vertical member secured within the lower end of the central cylindrical member and extending downwardly through the choke ring, a second die member carried by the lower end of the vertical member, and a die head working in combination with the die for forming a socket on the end of the pipe and supporting the pipe during its formation by the die.
15. A pipe press comprising a clay cylinder, a choke ring secured to the lower end of the cylinder, an arch member supported within the ring and formed with a number of webs, a vertical cylindrical hollow member formed integral with the webs, a choke ring carried by the arch member, and having its upper inner wall converging inwardly and diverging outwardly, a die member carried by the lower end of the choke ring, a vertical member secured in the central cy-

4
lindrical hollow portion of the webs and extending downwardly through the choke ring, a second die member carried by the lower end of the vertical member, a knife shaft passing upwardly through the vertical member, a beveled gear carried by the upper end of the shaft, within the central hollow cylindrical portion of the webs, a second

beveled gear meshing with the first gear, and a horizontal shaft passing out through one of the webs and through the arch member. 10

In testimony whereof, I have signed this specification.

THOMAS A. HIBBINS.
